D. L. ERNST

SOIL FITTING

Filed Aug. 27, 1925

INVENTOR,
D. L. Ernst;
BY *F. S. Maynard,*
ATTORNEY.

UNITED STATES PATENT OFFICE.

DANIEL LOT ERNST, OF LOS ANGELES, CALIFORNIA.

SOIL FITTING.

Application filed August 27, 1925. Serial No. 52,924.

This invention relates to plumbing apparatus and especially to soil fittings.

One standard type of fitting consists of a combination Y and eighth turn bend having 5 on its top end and on its lateral end what are termed "hubs" into which are inserted and packed and leaded ends of contiguous fittings.

In installing the common Y and eighth 10 bend fitting it is frequently necessary to cut into or through a girder on which the floor joists rest. One object of my invention is to eliminate this injurious step.

When a common bend of this type is used 15 its top "hub" comes just below the floor planks and a short piece of tube called a "stub" is set in the top "hub" and its lower end is packed and leaded tight. Then the usual flanged "closet ring" is fitted and packed and leaded around the top end 20 of the "stub" which extends up into the flooring. A second object of my invention is to eliminate this separate "stub" and also the necessary packing and leading of it in 25 the top of the Y hub, by extending up the trunk of the Y to directly receive the "ring" and enable the latter to be packed and leaded directly into the Y head.

The trunk of the Y usually stands vertical 30 and the lateral vent opening from it allows the sewage material to flow out laterally to the vent line. Therefore, another object 35 of my invention is to provide a lip, which extends down to the bottom horizontal line of the lateral vent of the bend and so cut off lateral flow from the vertical trunk. And in this connection an object is to provide 40 an ample area of air outlet lateral from the trunk while at the same time choking off lateral sewage escape to the vent.

Figure 1 is a side elevation of the fitting.
Figure 2 is a plan or top view.

Figure 3 is a longitudinal or "half section."

Figure 4 is an elevation of the installed invention.

The fitting consists of a straight trunk 2 from the side of which extends a Y branch 3 with an "eighth" turn terminating in a hub

4 which has its end parallel to the axis of 50 the trunk 2. Ordinarily, when installing the hub 4 under a floor on 6 inch joists it is necessary to cut away the girder to clear the "hub", because a stub (not shown) is let into the top of the usual head of the Y 55 fitting.

In order to eliminate the "stub" and its necessary packing I extend the top end 5 of the trunk 2 up well above the top of the lateral "hub" 4 so that the head or top 60 of the Y is in the floor opening.

This permits the hub 4 to lie between the floor and girder without cutting away the latter. The exterior of the head of the trunk is corrugated at 6 to help make a tight joint 65 with an applied ring.

As clearly seen in the sectional view, a lip 8 extends down, at the mouth of the lateral branch 3, to a point level with the bottom of the eighth bend so that lateral surging 70 of sewage through the vent is prevented.

To obtain ample vent area of opening the opposite sides of the vent branch are materially bulged at 9, as clearly seen in the top plan, Fig. 2.

From the above it will be seen that I have provided means to prevent cutting a girder; to eliminate a "stub" member and its cost of labor and material for packing; and I provide for stopping side escape of sewage 80 to vent and still provide ample air vent.

What is claimed is:

A soil and vent plumbing apparatus including a soil fitting having a substantially straight, continuous main vertical tube 85 whose lower end is insertible into the socket of a contiguous soil pipe and whose upper end is attachable to the base of a closet, one side of the tube having a Y-branch ending in a hub whose axis is substantially perpendicular to the tube for attachment of a venting elbow superjacent a floor girder; whereby cutting of the girder is eliminated; the upper part of the said tube ending in a plane above the said hub, and a curtain wall 90 at the mouth of the branch.

DANIEL LOT ERNST.
